CLAIM

The ornamental design for “door plate”, as shown and described.

DESCRIPTION

FIG. 1 is a top plan view of a first embodiment of a design of the door plate

FIG. 2 is a bottom plan view of the door plate illustrated by FIG. 1;

FIG. 3 is a side elevational view of the door plate illustrated by FIGS. 1 and 2;

FIG. 4 is a front elevational view of the door plate illustrated by FIGS. 1, 2, and 3;

FIG. 5 is a perspective view of the door plate illustrated by FIGS. 1, 2, 3, 4, and 5;

FIG. 6 is a top plan view of a second embodiment of a design of the door plate;

FIG. 7 is a bottom plan view of the doorplate illustrated by FIG. 6;

FIG. 8 is a side elevational view of the doorplate illustrated by FIG. 6;

FIG. 9 is a front elevational view of the doorplate illustrated by FIG. 6;

FIG. 10 is a perspective view of the doorplate illustrated by FIG. 6;

FIG. 11 is a top plan view of a third embodiment of a design of the door plate;

FIG. 12 is a bottom plan view of the doorplate illustrated by FIG. 11;

FIG. 13 is a side elevational view of the doorplate illustrated by FIG. 11;

FIG. 14 is a front elevational view of the doorplate illustrated by FIG. 11; and,

FIG. 15 is a perspective elevational view of the doorplate illustrated by FIG. 11.

The door plates illustrated by FIGS. 1–15 are of the type which are mountable to a vertical structure such as a door, door frame, or wall proximate to a door, for receiving sheets of material with identifying indicia such as the identification of the room and/or the identification of a person occupying the room.
